(57) **CLAIM**

The ornamental design for a display screen or portion thereof with graphical user interface, as shown and described.

DESCRIPTION

The FIGURE is a front view of a display screen or portion thereof with graphical user interface showing my new design. The broken line drawing of the portion of the display screen shown in The FIGURE is for illustrative purposes only and forms no part of the claimed design. The rectangular area appearing in white forms no part of the claimed design.

1 Claim, 1 Drawing Sheet
